DESIGN FOR A WALKER

Emanuel T. Batko, Chicago, Ill., assignor to Roxy Manufacturing Company, Chicago, Ill., a co-partnership composed of Sylvia Stein, Emanuel T. Batko, and Al Stillman

Application April 27, 1946, Serial No. 129,051

Term of patent 3½ years

(Cl. D34—15)

To all whom it may concern:

Be it known that I, Emanuel T. Batko, a citizen of the United States and resident of Chicago, in the county of Cook and State of Illinois, have invented a new, original, and ornamental Design for a Walker, of which the following is a specification, reference being had to the accompanying drawing, forming a part thereof.

Fig. 1 is a perspective view of a walker showing my new design.

Fig. 2 is a top view thereof slightly in perspective.

I claim:

The ornamental design for a walker, substantially as shown.

EMANUEL T. BATKO.
